UNITED STATES PATENT OFFICE.

HENRY WACHTMANN, OF CHICAGO, ILLINOIS.

BOWLING-TABLE.

No. 839,440.

Specification of Letters Patent.

Patented Dec. 25, 1906.

Application filed June 25, 1906. Serial No. 323,218.

To all whom it may concern:

Be it known that I, HENRY WACHTMANN, a citizen of the United States, residing at Chicago, in the county of Cook and State of Illinois, have invented a new and useful 5 Bowling-Table, of which the following is a specification.

My invention relates to a new bowling-game which may be played on a table, as illustrated in the accompanying drawings, or on a 10 regular bowling-alley, with the slight modification that in the game played on the table a cue may be used, while on the bowling-alley the ball is rolled by hand, as is customary.

15 The object of my invention is to provide a means for harmless and interesting amusement in the house or on the bowling-alley, affording at the same time healthy and active exercise. I attain these objects by the 20 game-table illustrated in the accompanying drawings, in which—

Figure 1 is a perspective view of the bowling-table, showing the pins in position. Fig. 2 is a plan view of the top of the table; and 25 Fig. 3 is a detail of the partition for one of the runways, showing its protecting rubber cushion at the outer edge.

Similar letters and figures refer to similar parts throughout the several views.

30 The table A is of the rectangular shape of a billiard-table. It is mounted upon substantial legs B and secured thereto. The top board 1 is bordered by rail 2, which is provided with elastic cushions 3. A partition 4 divides the center board into two fields C and D. This partition commences at the foot end of the table and runs up toward the head end throughout about three-fourths of its 35 length. It is provided with an elastic cushion 4' on both sides and is capped with a semicircular top 4². Around top 4² a number of semicircular partitions 5 are so placed and secured with the board 1 as to provide a corresponding number of semicircular runways 6, 6', 6², 6³, and 6⁴. The outermost 45 point of partitions 5 in field D is provided with an elastic cushion 5', as shown in Fig. 3. In field C, at the foot end of the table, are located a plurality of pins 7. These pins may 50 be placed in groups of various forms. In the illustration ten pins are shown forming a group of triangular shape.

The ball 8, with which the pins in the adjacent field are to be thrown, is placed with- 55 in a certain marked space in field D, and the shooting of the ball is effected by means of a

cue 9. When the ball strikes the mouth of any of the runways, each of which is slightly widened for that purpose, it follows the narrow course of the latter, passes into field 60 C, and runs into the group of pins, throwing a number of them. Those pins which retained the erect position must then be thrown by directing the ball accordingly and shooting it through the corresponding runway. When the ball strikes any one of the elastic cushions 5', with which partitions 5 are provided at the mouth of each runway in field D, it is repelled thereby and returns to the foot end of the table. Should it be nec- 65 essary to facilitate the speed of the ball after same has passed one of the runways, it is only necessary to slightly pitch field C to- 70 toward the foot end of the table. The game may be played with one or a plurality of pins, 75 as well as upon a table having one or a plurality of runways. It will also be appreciated that the same method of shooting the ball through narrow runways into an adjacent field for the purpose of throwing a group of 80 pins or only one of them, as the case may be, is applicable to bowling-alleys as well, and that owing to the identity of the two pur- 85 poses a description of the game when played on a table has been deemed sufficient. It will be apparent that the player may take 90 care of the pins himself in either case, as same are located at the foot end of either the table or the bowling-alley and within easy reach of the player, so that a person may readily 95 amuse himself without further assistance. It is also apparent that changes in the construction of the table may be made without departing from the scope of the above invention. 95

Having thus fully described my invention, what I claim as new, and desire to secure by Letters Patent, is—

1. In a bowling-table, the combination, of a center board 1, with an elevated partition 4, a semicircular elevated top piece 4², a semi- 100 circular elevated partition 5 forming a runway with the said top piece 4², an elastic cushion 5' inserted into the outermost point of the said partition, substantially as de- 105 scribed.

2. In a bowling-table, the combination, of a center board 1, with an elevated partition 4, a semicircular elevated top piece 4², a plu- 110 rality of semicircular elevated partitions adapted to form runways, an elastic cushion 5 inserted into the outermost points of each

of the said partitions, substantially as described.

3. In a bowling-table, the combination, of a center board 1, with an elevated partition 4, a semicircular elevated top piece 4², a plurality of semicircular elevated partitions adapted to form runways and so arranged as to be slightly wider at the entrance to each runway, an elastic cushion 5 inserted into the

outermost point of each of the said partitions, substantially as described.

In testimony whereof I have signed my name to this specification in the presence of two witnesses.

HENRY WACHTMANN.
